CLAIM

The ornamental design for a bicycle chain ring as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of the invented bicycle chain ring. FIG. 2 is a magnified view of the region of FIG. 1 indicated by the dashed lines.

FIG. 3 is a back view of the invented bicycle chain ring. FIG. 4 is a magnified view of the region of FIG. 3 indicated by the dashed lines.

FIG. 5 is a top view of the invented bicycle chain ring. FIG. 6 is a magnified view of the region of FIG. 5 indicated by the dashed lines.

FIG. 7 is a bottom view of the invented bicycle chain ring. FIG. 8 is a magnified view of the region of FIG. 7 indicated by the dashed lines.

FIG. 9 is a left side view of the invented bicycle chain ring. FIG. 10 is a magnified view of the region of FIG. 9 indicated by the dashed lines.

FIG. 11 is a right side view of the invented bicycle chain ring.

FIG. 12 is a magnified view of the region of FIG. 11 indicated by the dashed lines.

FIG. 13 is a front perspective view of the invented bicycle chain ring; and,

FIG. 14 is a magnified view of the region of FIG. 13 indicated by the dashed lines.

The broken lines in the drawings do not represent any forms of structures and are included solely for the annotative purpose of indicating the areas of enlargement. As the broken lines do not represent actual structures, they are not part of the claimed design.
